UNITED STATES PATENT OFFICE.

DANIEL McDICKEN, OF BROOKLYN, NEW YORK.

CONCRETE WALL CONSTRUCTION FOR BUILDINGS.

1,060,272.

Specification of Letters Patent. Patented Apr. 29, 1913.

Application filed February 15, 1913. Serial No. 748,505.

To all whom it may concern:

Be it known that I, DANIEL McDICKEN, a citizen of the United States, and residing at Brooklyn, in the county of Kings and 5 State of New York, have invented certain new and useful Improvements in Concrete Wall Constructions for Buildings, of which the following is a specification, such as will enable those skilled in the art to which it 10 appertains to make and use the same.

This invention relates to concrete building walls, and the object thereof is to provide a building wall of this class which is reinforced and which consists of a concrete 15 body inclosing a wooden frame which is water or moisture proofed on the outer side, and whereby the entire wall is made water proof or moisture proof from the outer side, and with this and other objects in view the 20 invention consists of a wall of the class specified constructed as hereinafter described and claimed.

The invention is fully disclosed in the following specification of which the accompanying drawing forms a part, in which the separate parts of my invention are designated by suitable reference characters in each of the views, and in which:—

Figure 1 is a horizontal section of the 30 frame portion of a building wall made according to my invention and before the concrete is applied and showing one corner and two adjacent walls;—Fig. 1^a a view similar to Fig. 1, but showing a modification of the corner construction and with parts omitted;—Fig. 2 a vertical section on the line 2—2 of Fig. 1 and showing a completed wall;—Fig. 3 a view similar to Fig. 1 with parts omitted and showing the molding boards between which, in practice, the concrete is placed, said figure being also a horizontal section on the line 3—3 of Fig. 4, and;—Fig. 4 a vertical section on the line 4—4 of Fig. 3.

45 In the practice of my invention I first provide sills *a* which are laid in the usual manner, but which are first wrapped in tar felt or other moisture proofing material, as shown at *b*. On these sills are placed vertical stanchions *c* which are also wrapped with tar felt *b*, and in Fig. 1 two of these stanchions are used to form a corner *c*², and these stanchions are also wrapped with tar felt *b*.

50 Between the stanchions *c* and the corner *c*² is placed a partition *d* consisting of ver-

tically placed boards or panels, as shown in Fig. 2, and the outer side of this partition is also covered with tar felt *b* or other suitable water proofing material.

60 On the opposite sides of the stanchions *c* and on two inner sides of the corner *c*² and on the inner sides of the partitions *d* are secured vertical laths, *e*, and these laths *e* serve to hold the boards of said partition 65 against inward movement, and in practice, said partition boards are placed in position as the concrete is poured in, or as the wall is built up, and this concrete serves to hold said partition or the boards thereof against 70 outward movement, or said partition or the separate parts thereof may be secured to the laths *e*.

75 Before the concrete is poured in, the wall frame is inclosed by wires *f* which are arranged in staggered relation on the inner and outer sides of said frame, as shown in Fig. 2, and which are also arranged horizontally and are secured to the stanchions and the corners by staples or similar devices 80 *f*². After the inner frame has been completed in this manner, the molds are arranged, as shown in Figs. 3 and 4, so as to inclose said frame. These molds consist of an outer member *g* consisting of separate parts *g*² built up from the bottom of the wall to the top thereof, and an inner member *h* consisting of separate parts *h*² built up from the bottom as the casting or pouring in of the concrete continues, a portion of said concrete being poured in and allowed to set, after which the inner mold member *h* is built higher and another portion of the concrete poured in and allowed to set, and this operation is continued until 90 the wall is completed.

95 Before the casting or pouring in of the concrete begins, the outer mold member *g* is inforced by vertical stanchions *i* which are bound to corresponding wall frame 100 stanchions *c* by means of wires *i*², as clearly shown in Fig. 3, and after the wall has been cast, or the concrete poured in and allowed to set, the wires *i*² are cut and the stanchions *i* removed together with the outer 105 mold member *g*, after which the wires *i*² are cut off close up to the adjoining face of the concrete wall, after which the finish of the wall is applied.

110 In order to regulate the thickness of the concrete walls and to provide means whereby the concrete of both the outer and inner

sides of the frame will be of a proper or desired thickness, I secure between the wooden frame and the mold boards, or mold members, g and h , vertical strips j of the desired thickness, and after the mold members have been taken away, as hereinbefore described, and before the finish is applied to the walls, these strips are cut out or dug out, and the narrow grooves in the concrete wall produced by the removal of these strips are filled in by the finish applied to the surface of the concrete wall.

In Fig. 1^a I have shown a corner construction which may be substituted for that shown in Fig. 1, if desired. In this figure I have shown the sills a and a floor beam, or a floor and ceiling beam k , and its "support plate" k^2 and in this form of construction, I provide corner stanchions m and n . The inner corner of the stanchion n is preferably cut away, as shown at n^2 , and secured to the other stanchion m is a vertical supplemental stanchion m^2 , and between these stanchions are placed vertical boards or panels o which are arranged in the form of an L, and which supplement the panels or partitions d , and the stanchions m , n and m^2 are covered with tar felt b , and the boards or panels o are also covered on their outer sides by the same material. With this form of construction the actual corners will be composed of solid concrete columns, whereas, with the construction shown in Fig. 1, the corner is principally composed of the stanchions c , and the construction

shown in Fig. 1^a will probably be the preferred construction.

My invention is not limited to the exact details of the inner frame work of my improved wall construction, as herein shown and described, nor to the exact method of, or means for casting the concrete around said frame, and changes in and modifications of the construction herein described may be made, within the scope of the appended claim, without departing from the spirit of my invention or sacrificing its advantages.

Having fully described my invention what I claim as new and desire to secure by Letters Patent is:—

A herein described building wall construction, comprising a framework of wood, consisting of corner posts, spaced stanchions and intermediate panels, said framework of wood being covered on the outer side thereof with waterproof material and being entirely inclosed on the inner and outer sides thereof by concrete, said concrete being reinforced by material secured to the inner and outer sides of the corner posts and stanchions.

In testimony that I claim the foregoing as my invention I have signed my name in presence of the subscribing witnesses this 13th day of February, 1913.

DANIEL McDICKEN.
